CLAIM

The ornamental design for a tripod camping fan as shown and described.

DESCRIPTION

FIG. 1 is a front, top, right side perspective view of a tripod camping fan showing my new design;

FIG. 2 is another front, top, right side perspective view of the tripod camping fan of FIG. 1, shown in an environment of use;

FIG. 3 is a rear, top, right side perspective view thereof;

FIG. 4 is a front view of the tripod camping fan of FIG. 1;

FIG. 5 is a rear view thereof;

FIG. 6 is a left side enlarged view thereof;

FIG. 7 is a right side enlarged view thereof;

FIG. 8 is a top view thereof;

FIG. 9 is a bottom view thereof;

FIG. 10 is an enlarged detail view of encircled area 10 of FIG. 1;

FIG. 11 is an enlarged detail view of encircled area 11 of FIG. 4; and,

FIG. 12 is an enlarged detail view of encircled area 12 of FIG. 5.

The broken lines shown on the drawings depict portions of the tripod camping fan that form no part of the claimed design. In FIGS. 2 and 3, the broken lines depict the environment in which the tripod camping fan is used that form no part of the claimed design. The dot-dash lines depict the enlarged view boundaries that do not form part of the claimed design.
